INVENTOR.

HARRY LEE.
By *Arthur L. Slee*.
ATTY.

UNITED STATES PATENT OFFICE.

HARRY LEE, OF SAN FRANCISCO, CALIFORNIA.

DRAIN FIXTURE.

Application filed June 8, 1925. Serial No. 35,552.

My invention relates to improvements for drain fixtures for shower baths and the like wherein the flanged edge of an outlet of a floor lining is firmly clamped against the 5 flange of a tray formed in connection with a drain pipe whereby leakage of water over the edge of the tray may be prevented.

In providing drains for shower baths and the like wherein it is desired to drain water 10 downwardly through the floor it is difficult to obtain a water tight connection between the drain fixtures and the floor. This is particularly true and particularly objectionable in the case of shower baths such as installed in homes wherein any leakage around the drain not only rots the floor and framework of the building but often causes serious damage to the finish of adjacent or underlying rooms and furniture contained 15 therein. The primary object of my invention is therefore to provide a fixture which will effectually prevent leakage around the edge of the drain.

Another object is to provide an improved 25 device of the character described which may be easily installed and which will facilitate the cleaning of the drain when necessary.

A further object is to provide an improved construction which can be economically 30 manufactured and which will form an efficient and leak proof drain.

I accomplish these and other objects by means of the device disclosed in the drawings forming a part of the present specification 35 wherein like characters of reference are used to designate similar parts throughout said specification and drawings and in which,

Fig. 1 is a broken plan view of my improved drain fixture, and

Fig. 2 is a vertical section of the drain as shown in Fig. 1.

Referring to the drawings, the numeral 1 is used to designate in general a drain pipe 45 provided with a tray 2 formed adjacent the upper end thereof. The tray is arranged to be supported upon the floor supporting structure 3 with the upper edge of an annular flange 4 formed upon the edge of the tray arranged level with the upper surface of the floor boards 6 of a shower bath or the like from the floor of which it is desired to drain water.

A lining 7 made of ductile metal or other 55 suitable material is laid upon the floor of the shower bath in the well known manner

said lining being provided with a downwardly disposed annular flange 8 formed around the edge of an opening arranged to register with the drain, said flange being 60 adapted to fit against the inner surface of the tray flange 4.

The upper end of the drain pipe 1 extends slightly above the bottom of the tray 2 and has a plurality of openings 9 formed therein 65 to permit water to drain from the tray into the pipe. The upper end of the pipe is threaded, as at 10.

A cover 11 is mounted upon the threaded end of the drain pipe, said cover being 70 adapted to fit the recess formed in the floor by the tray 2 and the downwardly disposed flanged edge 8 of the lining. The edge of the cover 11 is shaped to form a downwardly disposed flange 12 adapted to engage the inner surface of the flange 8 and a plurality of apertures 14 are formed in the cover to permit the drainage of water into the tray.

The tray flange 4 is preferably shaped to 80 diverge toward the upper edge thereof and the flanges 8 and 12 of the lining and the cover are shaped to conform to the inclination of the tray flange. The cover is preferably arched slightly toward the center and 85 is made of material preferably having a spring resilience whereby the cover may be pressed downwardly into the recess and thereby firmly clamp the lining flange 8 against the tray flange 4. This is accomplished by means of a nut 16 threaded onto the end of the pipe 1. As the nut 16 is advanced against the cover the cover is moved downwardly and the flange 12 wedged against the flange 8 whereby said flange 90 is pressed firmly against the tray so as to form a water tight connection therewith. The arched shape and the spring resilience 95 of the cover permit the cover to be pressed against the lining flange with sufficient pressure to insure against any possible seepage of water between the flanges 8 and 4 and thence over the edge of the flange 4.

The upper end of the drain pipe is closed by means of a plug 17 having apertures 18 formed therein, said plug being removable to permit cleaning of the pipe 1 when necessary.

In operation, the water from the shower drains through the apertures 14 in the cover into the tray and thence into the drain pipe 1 through the apertures 9. Should the aper-

tures 9 become clogged by lint or other solid material washed through the apertures 14 of the cover or should water be admitted faster than it can drain away, the water will not rise between the flanges 4 and 12 as in the ordinary drain fixtures heretofore commonly used in installations of this type, but will be effectually retained until the water has time to seep away. When the drain becomes clogged in any way the cover 11 may be readily removed by unscrewing the nut 16 from the end of the pipe 1, thereby permitting the cover to be removed and access had to the tray for cleaning. When the cover is replaced the flanges will be clamped again to form a water tight connection, thereby maintaining the efficiency of the drain.

The specific form and construction of the several elements of my invention are of course subject to modification in various ways without departing from the spirit of my invention. I therefore do not wish to restrict myself to the specification details of construction which are herein disclosed, but desire to avail myself of all modifications which may fall within the scope of the appended claims.

Having thus described my invention what I claim as new and desire to secure by Letters Patent is:

1. A drain for shower baths and the like comprising a floor lining having an opening and downwardly converging annular

flange formed around the opening; a drain pipe; a tray formed adjacent the upper end of the pipe and provided with an upwardly diverging annular flange adapted to engage the lining flange; an apertured cover mounted in connection with the upper end of the drain pipe and provided with a flange edge engaging the inner surface of the lining flange; and a nut threaded onto the upper end of the drain pipe to press the cover against the lining and thereby wedge the lining flange against the tray flange to prevent leakage of water thereover.

2. A drain for shower baths and the like comprising a floor lining having an opening and downwardly converging annular flange formed around the opening; a drain pipe; a tray formed adjacent the upper end of the pipe and provided with an upwardly diverging annular flange adapted to engage the lining flange; an apertured cover mounted in connection with the upper end of the drain pipe and provided with a flange edge engaging the inner surface of the lining flange; and a nut threaded onto the upper end of the drain pipe to press the cover against the lining and thereby wedge the lining flange against the tray flange to prevent leakage of water thereover; and an apertured plug fitted into the upper end of the drain pipe.

In witness whereof I hereunto set my signature.

HARRY LEE.
